UNITED STATES PATENT OFFICE.

ARMAND MAUCHAIN, OF GENEVA, SWITZERLAND.

ADJUSTABLE DESK AND SEAT FOR SAME.

SPECIFICATION forming part of Letters Patent No. 340,341, dated April 20, 1886.

Application filed February 28, 1885. Serial No. 157,233. (No model.)

To all whom it may concern:

Be it known that I, ARMAND MAUCHAIN, a citizen of the French Republic, residing at Geneva, Switzerland, have invented a new 5 and useful Transformation School-Desk, with Movable Bench, of which the following is a specification.

In the accompanying drawings, Figure 1 shows the transformation desk with school-10 bench disposed as a drawing-table for aged scholars. Fig. 2 shows the disposition of said desk with horizontal table and lifted seat to work standing. Fig. 3 shows the disposition of the back of the seat permitting to regulate 15 the depth of the seat according to the size of the scholar. Fig. 4 shows the desk provided with an etagère. Fig. 5 shows a cut through X Y, representing the disposition of rollers T and U in view of facilitating the sliding of 20 the bearings C C.

In all the figures the same letters refer to the same parts.

The standards A A of the desk are combined with a plank, B, which may be inclined, serving as a foot-rest. These standards A A are provided on their insides with slides, in which 25 slide the secondary standards C C, supporting the box D of the desk. The secondary standards C are provided with slits c, through which 30 pass the bolts d, affixed in the standards A. With the help of these bolts the secondary standards C may be clamped at whatever height 35 may be desired.

The box D is closed on five sides and open on 40 the front when the table Y of the desk is in a horizontal position. The box D is closed on all sides when the table Y is inclined to the greatest extent, as indicated in Fig. 1. The table Y of the desk, which may be employed 45 as a drawing-board, is connected at the ends of the box D by means of flanges E, secured to the ends of the box D by pivot-screws. The inkstand G may be removed when the table Y is turned down flat. The table Y and the 50 end flanges, E, may be swung upon the pivots into a greater or less inclined position.

The pivot pins or screws are placed in such a manner that the table Y will swing forwardly and downwardly automatically, and thereby 55 close or cover the box D.

To provide for fixing the table Y of the desk

either in the horizontal position represented in Fig. 2 or in a position less inclined than that shown by Fig. 1, the flanges E are provided with eccentric prolongations E', formed 55 as an arc of a circle, against which the bolt h is forced by the handle i.

According to the position of the hole into which the bolt h may pass the table of the desk will occupy a more or less inclined position. 60 It will always be possible to swing the tabletop i into a horizontal position to take something out of the box.

The construction of the flange E may be such 65 as shown in Fig. 1.

To facilitate the raising and lowering of the desk, the same is provided with a screw, H, supporting the box D and provided with nut, I, resting upon the top of the hollow post J. Upon turning the nut I, after having loosened the bolts d d, the desk is raised to the desired height, in which it is then fastened by means of said bolts d d.

The screw H, with nut I and hollow post J, 75 may be a fixture with the desk, or they may be movable. If removable, the same screw may be used for several desks.

All the parts of the described desk may be 80 made of wood or of metal and formed more or less elegantly.

The movable seat is composed of two bearings, K, connected together by a cross-bar, N, and by a board, L, in which there are two ranges of holes, l, through which pass the bolts m' of the seat M. The back O may be affixed 85 in whatever height desired with the help of the screws o, Fig. 1, which pass through slits k of the bearings K, or by means of the hooks o', as shown by dotted lines in Fig. 3.

The seat M is formed of two parts, the one 90 of which, M', may be raised as it is shown in Fig. 3. The latter shows that by a rational choice of the angle x' the depth of the seat is always proportional to its height. When the seat and the back are both in the highest position, the depth of the seat is x, and when seat and back are both fixed in the lowest position the depth of the seat is only y.

In cases in which the following described manner of affixing the feet of the seat in a variable distance to those of the desk is found 95 too expensive, the angle y' may be chosen

in a manner as to cause the seat to approach to the desk when the same is affixed lower, as it is shown by dotted lines in Fig. 3.

The foot-pieces of the seat are connected to those of the desk by means of the sliders Q.

I do not claim a seat in which there are bars sliding vertically in slotted legs and held by pins, and to which bars the seat is connected by links, as such a device is shown in German Patent No. 11,541.

I am aware that desks and tables have been made to be inclined or raised or lowered, and that the seat has been adjustable nearer to or farther from the desk, and that seats have been variable in height.

I claim as my invention...

1. In combination with a tipping desk-top, Y, slotted standards c, standards A, bolts d, and plank or rest B, the screw H, nut I, and post J, beneath the desk, for raising or lowering the same and firmly supporting such desk in addition to the support from the standards, as set forth. 20

2. The combination, with the hinged seat M', the standards K, and cross-board L, having 25 vertical rows of holes in the same, and the attaching-bolts m', for varying the height of the seat, substantially as set forth.

ARMAND MAUCHAIN.
